UNITED STATES PATENT OFFICE.

CHARLES PFANSCHMIDT, OF CHICAGO, ILLINOIS, ASSIGNOR TO THEO. A. KOCHS CO., OF CHICAGO, ILLINOIS, A CORPORATION OF ILLINOIS.

DESIGN FOR A SEAT-FRAME FOR BARBERS' CHAIRS.

46,064.

Specification for Design.

Patented July 7, 1914.

Application filed December 12, 1913. Serial No. 806,350. Term of patent 7 years.

To all whom it may concern:

Be it known that I, CHARLES PFANSCHMIDT, a citizen of the United States, residing at Chicago, in the county of Cook and State of Illinois, have invented a new, original, and ornamental Design for Seat-Frames for Barbers' Chairs, of which the following is a specification, reference being had to the accompanying drawing, forming a part thereof.

In the drawing: Figure 1 is a perspective

of the seat frame with a cushion shown in dotted lines; and Fig. 2 is a plan view of the seat frame with a cushion shown in dotted lines.

I claim:

The ornamental design for a seat frame for barbers' chairs, substantially as shown.

CHARLES PFANSCHMIDT.
